[57] CLAIM

The ornamental design for a technical pen adapter,
substantially as shown and described.

DESCRIPTION

FIG. 1 is a perspective view of a technical pen adapter
showing our new design;

FIG. 2 is a right side elevational view thereof, the
environmental structure shown in dotted lines depicting the
barrel and head of a technical pen is for illustrative
purposes only and not a part of the design;

FIG. 3 is an enlarged scale top plan view thereof;

FIG. 4 is an enlarged scale left side elevational view
thereof; and

FIG. 5 is a front elevational view thereof.
